(57) **CLAIM**

The ornamental design for a portable electronic flare system, as shown.

DESCRIPTION

FIG. 1 is a perspective view of a portable electronic flare system showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front view of the design shown in an alternate position; and,

FIG. 9 is a rear view thereof.

The size of the carrying case may vary to accommodate differing numbers of flares.

The shapes of the flares may vary from the exemplary round and rectangular shapes shown in the drawings, and may include ovoid or polygonal shapes.
